IRONING TABLE TOP

Horace B. Fay, Willoughby, Ohio, assignor to
 Gridiron Steel Company, Cleveland, Ohio, a
 corporation of Ohio

Application October 29, 1947, Serial No. 782,919

2 Claims. (Cl. 38—137)

1

The present invention, relating as indicated to an ironing table top, is more particularly directed to a new light weight, metallic ironing table top made from a single, continuous and regularly deformed sheet that serves both as an ironing surface, when covered with a suitable pad, and as a structural member of the assembly.

The principal object of the present invention is to provide a metal ironing table top made from a single deformed sheet that may be attached to any of a variety of legs or stands in such a manner that a smooth ironing surface with sufficient structural strength and rigidity can be produced at the lowest cost and least weight.

A further object is to make use of a single, continuous metal sheet by deforming or corrugating the sheet in a regular but staggered conformation of only slight depth so as to give structural strength to the top sheet without making it so rough that it cannot be used as an ironing surface.

A further object is to provide an ironing surface with the minimum structural weight while at the same time providing a surface strong enough for ironing. For the purpose of this application a "deformed sheet" is defined as one containing depressions out of the normal plane of the sheet in some regular but staggered conformation such as buttons, corrugations or diamond shape depressions in such a manner that no straight line can be drawn from side to side, end to end or side to end without passing through a series of depressions.

It has been found that a perfectly flat or smooth surface is not necessary in ironing where the usual pad is being used. This surface need not be smooth and in having a deformed sheet it is possible to provide greater structural strength in a single sheet. The indentations in this deformed sheet would then be filled or bridged by the body of the ironing pad, without forming any exact corresponding depressions in the pad sufficient in width or depth to mark the clothes.

To the accomplishment of the foregoing and related ends, said invention, then, consists of the means hereinafter fully described and particularly pointed out in the claims; the annexed drawings and the following description setting forth in detail certain structure embodying the invention, such disclosed means constituting, however, but one of various structural forms in which the principle of the invention may be used.

2

Fig. 1 is a plan view of an ironing table top with a portion of the top sheet removed showing the ribs;

Fig. 2 shows a fragmentary cross-section of Fig. 1 along the line 2—2 of Fig. 1;

Figs. 3 and 4 are cross-sections of other forms of an ironing table, showing various alternate forms of construction, including types of edges, rib construction and surface sheets, and

10 Fig. 5 is a plan view of portions of an ironing table surface showing diamond shaped indentations on the left side and the same indentations with ventilated holes on the right side

Referring more particularly to the drawing, 15 Fig. 1 shows an ironing table top indicated generally at 10 with an ordinary tapered nose portion 22 having a rounded end 23. The butt end of the board 24 is flat except for the rounded corners 25. The table top comprises a metal

20 sheet reinforced by longitudinally extending ribs 12. The sheet 10 is deformed or indented in a regular but staggered conformation of buttons or dimples that have been pressed or rolled from the normal plane of the sheet as is clearly shown in Fig. 2. The sheet will be deformed over its entire area except for a marginal portion. However, in the drawings only a portion is shown

25 having deformations.

The sheet 10 illustrated in Figs. 1 and 2 consists of buttons or dimples 13 pressed or rolled out of the plane of the sheet in the form of a hemisphere arranged in a staggered pattern so that there is no continuous line unbroken by a series of deformations or buttons. These deformations extend over the entire top sheet of the board to a point very near the edge of the board.

The buttons or deformations according to the invention may be pressed or rolled out of the 40 normal plane of the sheet and may be in total thickness up to fifteen times the thickness of the sheet or in practice in the art not more than one-half an inch in thickness.

The deformations 13 in the sheet consist of 45 alternate raised portions 30 and depressed portions 31. Planes passing through the extremes of the depressed and the raised portions will be separated by a distance equal to fifteen times the thickness of the sheet or one-half an inch at the most.

In one form of the invention the edge of the sheet 11 is turned down by rolling or bending to form a flange 14 which extends completely around the outside perimeter of the board. The 50 lower edge of flange 14 is rolled about a stiffen-

ing wire 29. This stiffens the outer flange of the board and provides a distinct lip with a smooth edge convenient for securing a top pad to the surface.

The sheet 10 and the ribs 12 are then securely fastened together at a number of points along the flanges 26 and 27 by spot welding or riveting. This construction of a deformed sheet and a supporting rib then make a stiff supporting structure capable of supporting the weight and pressure of ironing without substantial flexing.

As alternate constructions for stiffening the board about its edges, in Fig. 3 there is shown a sheet having a deep vertical flange 32 with a tubular end portion enclosing a solid rod 15. Still another form of construction is shown in Fig. 4 wherein the periphery is formed over a tubular structure 33. In Fig. 3 the rod 15 would add a greater weight and less rigidity than the hollow tube 16 of Fig. 4. Both would provide a rigid or semi-rigid flange to strengthen and support the edge of the board to prevent it from buckling under a heavy weight on the nose portion 22.

Referring now to Fig. 5 there is shown two other types of roughened or deformed sheets 10a and 10b serving both as structural assembly members and as an ironing surface. The section of sheet shown on the left side of Fig. 5 has diamond shaped indentations that are slightly staggered so there is no unbroken straight line remaining undeformed. These deformations in general are shallower than the deformations of Fig. 1 and may be more readily bridged and filled by the ironing pad. The section of the sheet shown on the right side of Fig. 5 is deformed similarly to that of sheet but in addition it is perforated in the approximate center of the indentations to permit the evaporation of moisture in the pad. These surface constructions can be fitted with any number of flanges or rib construction.

In Fig. 1 there is illustrated a plurality of parallel ribs 12 in this case three extending from the butt 24 of the board to the nose 23. These are approximately equally spaced and extend under the entire surface. The form of ribs I have chosen to illustrate is channeled ribs. They are composed of a lower flat horizontal portion 19 shown in Fig. 2 on the underside of the board

and two vertical wall sections 20 and 21 connected to the flange sections 26 and 27 extending laterally under the sheet.

I therefore particularly point out and claim as my invention:

1. A metal ironing table top comprising a single sheet of relatively thin sheet metal of the order of thickness heretofore used in two and three sheet tops and of a thickness insufficient to resist ordinary ironing pressures without substantial yield, and having a series of uniformly distributed relatively small deformations out of the normal plane of the sheet, said deformations serving to stiffen said sheet against bending in an area equal to the area of an ordinary iron, and having at least one longitudinally disposed rib connected to said sheet substantially parallel to its central longitudinal axis to stiffen said sheet against longitudinal bending under normal ironing loads.

2. A metal ironing table top comprising a single sheet of relatively thin sheet metal of the order of thickness heretofore used in two and three sheet tops and of a thickness insufficient to resist ordinary ironing pressures without yield, having a series of uniformly distributed relatively small deformations out of the normal plane of the sheet, said deformations serving to stiffen said sheet against bending in areas equal to that of an ordinary iron, and two longitudinally disposed ribs, said ribs being connected to said sheet substantially parallel to its central longitudinal axis to stiffen said sheet against longitudinal bending under normal ironing loads.
